UNITED STATES PATENT OFFICE.

WILLIAM A. HOGAN, OF NEW YORK, N. Y.

DESIGN FOR A SHADE FOR LAMPS.

No. 38,056.

Specification for Design.

Patented June 5, 1906.

Application filed January 28, 1905. Serial No. 243,147. Term of patent 7 years.

To all whom it may concern:

Be it known that I, WILLIAM A. HOGAN, a citizen of the United States, and a resident of New York, in the county of New York and State of New York, have invented a new, original, and ornamental Design for Shades for Lamps, which is illustrated in the accompanying sheet of drawings, wherein—

Figure 1 is a partial plan of a shade, looking from the top, one half of the shade being shown in full lines and the outline of the

lower edge of the other half being shown by a dotted line. Fig. 2 is a partial elevation of the shade, one-half being shown in side elevation.

I claim—

The ornamental design for a shade for lamps as shown.

WM. A. HOGAN.
